UNITED STATES PATENT OFFICE.

CHARLES LEO FITZ, OF FOND DU LAC, WISCONSIN, ASSIGNOR TO DROP HEAD PROJECTOR COMPANY, OF FOND DU LAC, WISCONSIN, A CORPORATION OF WISCONSIN.

HOUSING FOR PORTABLE MOTION-PICTURE MACHINES.

Application filed November 3, 1922, Serial No. 598,368. Renewed May 29, 1926.

This invention relates to an enclosing casing for portable motion picture machines and more especially to the type of such casing which constitutes the subject matter of 5 the McMillan Letters Patent No. 1,326,407 dated December 30, 1919, and this improvement has for its object:

To provide a structural formation and association of a skeleton reinforcing frame 10 adapted to afford a support for the wall portions of the enclosing casing of the machine, as well as a substantial support and pivotal and sliding connections of and for the drums or magazines of the film reeling 15 mechanism, the frame of the film feeding mechanism and the frame of the associated lamp house, all as will hereinafter more fully appear.

In the accompanying drawings:—

20 Fig. 1, is a perspective view of the skeleton frame of the present improvement.

Fig. 2, is a sectional elevation on line 2—2, Fig. 4 with the enclosing walls in place.

Fig. 3 is a detail perspective view of 25 parts at a corner of the skeleton frame, and showing adjoining ends of transverse and longitudinal rails in detached relation.

Fig. 4 is a horizontal section on line 4—4, Fig. 2.

20 Fig. 5 is a transverse section on line 5—5, Fig. 2.

Like reference numerals indicate like parts in the several views.

Referring to the drawings, 1 and 2 designate 30 counter part skeleton side members disposed in spaced relation with their outer faces formed with the hereinafter described recesses 4', 5', and 19', at their margins for the reception and support of the wall panels or sections of the rectangular enclosing casing of the machine. Each side member is of detail construction as follows:

3 designates a centrally arranged ring or annulus adapted to hold and support a film 45 drum or magazine of the machine, the ring 3 of one side member supporting the magazine of the film supply reel, and the companion ring 3 of the other side member supporting the magazine of the film take-up reel, with the magazine in transverse spaced relation as in the aforesaid Patent No. 1,326,407.

4 and 5 designate pairs of vertical and horizontal rails and with their external faces

formed with the heretofore referred to recesses 4' and 5' for the reception of the wall panels or sections of the enclosing casing. The rails 4 and 5 are integrally connected at their adjoining ends and also integrally connected to the aforesaid ring or annulus 3 to constitute a rectangular enclosing frame therefor as shown. In the preferred construction of the side members above described, the rails 4, 5 are cut away at their upper front corners with a removal of the vertical front rails 4 to a point below the mid-height of the skeleton supporting frame, and the upper part of each rail 4 is connected to a ring 3 by a longitudinal bracing rail 6, and such upper portions are formed with orifices for the pivotal attachment of the hereinafter described skeleton frame of the drop head of the machine and similar in purpose to the drop head of the aforesaid Patent No. 1,326,407.

In like manner the front portions of the horizontal top rails 5 of said side members are cut away a distance to the rear of the front of the frame, with the front end of said rails adapted to form stops or abutments for the drop head above referred to when said drop head is in its raised position.

7 designates diagonal rails connecting the front ends of the top rails 5 with the rings 3, and 8 designates a transverse rail connecting the forward ends of said rails 5 together and impose spaced relation thereon.

The ring 3 aforesaid, which carries the magazine of the film supply reel of the machine, is provided with an inwardly extending lug 9, formed with a transverse slot 9' open at its outer end and adapted to register with and form a part of the film inlet-outlet opening of said magazine. 95 While the companion ring 3 aforesaid, which carries the magazine of the film take-up reel of the machine, are provided with a pair of inwardly extending lugs 10 and 11 formed with transverse slots 10' and 11' 100 open at their outer ends and adapted to register with and form part of the respective film inlet opening and film outlet opening of said magazine, such construction is adapted to permit a change of the picture film from one to the other of said openings, in a change of the machine from a picture projecting operation to a film rewinding op-

eration and vice versa, as set forth in my companion application for patent Serial No. 598,865.

The skeleton side frames comprising the rings 3 and rails 4, 5 are fixedly connected together in proper spaced relation by a transversely arranged central frame having vertical members, horizontal members and transverse cross rails as follows:—

10 12 designates the horizontal connecting member of the central frame above referred to, formed with a pair of spaced guide rails or tracks 13, and with outwardly extending transverse bars or arms 14 adapted for 15 attachment to the bottom flanges of the lower rails 5 of the aforesaid skeleton side frames 1 and 2. The rear ends of the rails or tracks 13 are connected together and formed for fixed attachment to the herein- 20 after described transverse corner rails, and said tracks 13 are grooved or otherwise formed for guiding engagement with the carriage of a longitudinally adjustable lamp house such as described in McMillan Patent 25 No. 1,326,407 aforesaid.

15 15 designates the vertical member of the central connecting frame above referred to, of a plate form and having at its upper end outwardly extending arms 16 adapted for 20 attachment to the underside of the top flanges of the top rails 5 of the side members 1 and 2 aforesaid. Said member 15 is also provided with vertical strengthening ribs at its sides and with a pair of vertically 25 spaced orifices 17 and 18 for the passage of the light from the lamp house of the machine in the vertical adjustments of the lamp house as set forth in the McMillan Patent No. 1,326,408 of December 30, 1919.

40 40 The vertical member 15 is fixedly attached, preferably in an integral manner, to the horizontal members 12 aforesaid near the forward end of the same, with the lower end of the member 15 having a forked for- 45 mation 15' adapted to span the tracks 13 as shown more particularly in Figs. 1 and 5 and not impede a free movement of the lamp house carriage.

45 19 designates transverse connecting rails 50 arranged at the upper and at the lower rear ends and at lower forward end of the present structure and having a round corner right angle shape in cross-section and formed with recesses 19' in their external 55 faces for the reception of wall panels or sections of the enclosing casing as shown. At their respective ends the rails 19 are provided with right angle tongues or flanges 20 adapted to fit and be secured in 60 correspondingly formed recesses or grooves at the intersecting points of the rails 4, 5 of the skeleton side frames 1 and 2 as illustrated more particularly in Figs. 2 and 3.

65 21 designates the skeleton carrying frames of the drop head of the machine above re-

ferred to, and which is adapted to fit the space left by the omission of the upper portions of the vertical front rails 4, and the forward part of the upper horizontal rails 5 before described. In the preferred construction shown the frame 21 comprises integral- 70 ly connected parts as follows:—

22 designates a central web or plate portion formed with light passages 23, 24 corresponding to and aligned with the openings 75 17, 18 of the central connecting member 12 aforesaid.

25 designates side rails of an L shape and of an angular form in cross-section similar to that of the rails 4 and 5 aforesaid, so that with the drop head in the raised position shown in Fig. 2 the upper portion of said rails 25 constitute extensions of the upper horizontal rails 5 aforesaid, while the vertical portions of said rails 25 constitute ex- 80 tensions of vertical front rails 4 aforesaid to complete the rectangular box form of the enclosing casing and skeleton frame aforesaid. In the present construction the lower ends of the skeleton supporting frame are 85 pivoted to the upper ends of the front rails 4 by pivot pins passing through the rails 4 and the lower portions of the side rails 25 as shown.

26 designate stop arms extending downwards from the side rails 25 and adapted when the drop head is raised, to abut against the inner face of the side rails 4, to brace and stiffen the connection between the drop 90 head and the main casing.

27 designates a transverse rail similar in cross-section to the rails 4 and 5 above described, and arranged at the intersection of the angularly arranged portion of the side rails 25 to constitute the upper and 105 forward corner of the machine casing.

28 designates a transverse rail attached to the rear ends of the upper portions of the rail 25, and adapted for abutment contact with the transverse rail 8 of the side frame 110 1 and 2 aforesaid.

29 designates a transverse rail secured to the horizontal rails 5 midway between the rear ends of the same and the attachment of the central frame 12 aforesaid, to stiffen 115 and brace the rear portion of the skeleton frame and at the same time afford a substantial means of attachment of one end of the strap handle by which the machine is carried from place to place, the other end of the strap handle being attached to a central lug on the transverse arms 16 of the central frame 12 aforesaid.

30 designate rebates or recesses formed in the rails 4, 5 and 25 aforesaid, and near the rounded corners thereof, for the reception 120 of rectangular sheets of metal or the like to constitute in connection with said rails of the enclosing casing having a substantial and light formation.

Having thus fully described my invention, what I claim as new and desire to secure by Letters Patent is:—

1. In a skeleton supporting frame for the wall panels of the enclosing casing of a portable motion picture machine, a pair of skeleton side frames formed with central rings adapted to support the pair of film reel magazine of the machine, with vertical and horizontal rails integrally connected to said rings, and with transverse bracing means adapted to hold said side frames in spaced relation; said rails and bracing means having an angular form in cross-section with their external faces recessed to receive wall panels of the enclosing casing. 70
2. In a skeleton supporting frame for the wall panels of the enclosing casing of a portable motion picture machine, a pair of skeleton side frames formed with central rings adapted to support the pair of film reel magazine of the machine, with vertical and horizontal rails integrally connected to said rings, and with transverse bracing means adapted 75 to hold said side frames in spaced relation, one of said rings having a lateral lug formed with an open ended slot adapted to register with the inlet opening of a film take-up magazine, the other of said rings, having a pair of lateral lugs formed with open ended slots and adapted to register with the inlet and outlet openings of the film supply magazine. 80
3. In a skeleton supporting frame for the wall panels of the enclosing casing of a portable motion picture machine, a pair of skeleton side frames formed with central rings adapted to support the pair of film reel magazine of the machine, with vertical and horizontal rails integrally connected to said rings, and with transverse corner rails adapted to hold said side frames in spaced relation, said rails having an angular form 85 in cross-section with their external faces recessed to receive wall panels of the enclosing casing. 90
4. In a skeleton supporting frame for the wall panels of the enclosing casing of a portable motion picture machine, a pair of skeleton side frames formed with central rings adapted to support the pair of film reel magazine of the machine, with vertical and horizontal rails integrally connected to said rings, and with transverse corner rails 95 adapted to hold said side frame in spaced relation, said corner rails and the vertical and longitudinal rails having a round corner angular formation in cross-section and recessed on their external faces to receive wall panels of the enclosing casing. 100
5. In a skeleton supporting frame for the wall panels of the enclosing casing of a portable motion picture machine, a pair of skeleton side frames formed with central rings 105 adapted to support the pair of film reel magazine of the machine, with vertical and longitudinal rails integrally connected to said rings, and with transverse corner rails connecting the side frames in spaced relation, said corner rails and vertical and longitudinal rails having a round corner angular 110 formation in cross-section with their external faces recessed to receive wall plates of the casing. 115
6. In a skeleton supporting frame for the wall panels of the enclosing casing of a portable motion picture machine, a pair of skeleton side frames formed with central rings adapted to support the pair of film reel magazine of the machine, with vertical and longitudinal rails integrally connected to said rings, with transverse corner rails connecting the side frames in spaced relation, and a central connecting frame having at its lower end guide tracks for a longitudinally adjustable lamp house and with outwardly extending bars for attachment to the lower longitudinal rails of the side frames, and at its mid-width a vertical portion formed with light passages and having at its upper end outwardly extending bars for attachment to the upper longitudinal rails of the side frames. 120
7. In a skeleton supporting frame for the wall panels of the enclosing casing of a portable motion picture machine, a pair of skeleton side frames formed with central rings adapted to support the pair of film reel magazine of the machine, with vertical and longitudinal rails integrally connected to said rings, with transverse corner rails connecting the side frames in spaced relation, said corner rails and vertical and longitudinal rails having a round corner angular 125 formation in cross-section, and a central connecting frame having at its lower end guide tracks for a longitudinally adjustable lamp house and with outwardly extending bars for attachment to the lower longitudinal rails of the side frames, and at its mid-width a vertical portion formed with light passages and having at its upper end outwardly extending bars for attachment to the upper longitudinal rails of the side frames. 130

4
Light passages and having at its upper end outwardly extending bars for attachment to the upper longitudinal rails of the side frames, and a transverse rail attached to 5 said side frames and arranged midway between the rear ends of said frames and the vertical portion of the central connecting frame, said brace and central connecting frame affording a substantial attachment for 10 the carrying handle of the machine.

9. In a skeleton supporting frame for the wall panels of the enclosing casing of a portable motion picture machine, a pair of skeleton side frames formed with central rings 15 adapted to support the pair of film reel magazines of the machine, with vertical and longitudinal rails integrally connected to said rings, with transverse bracing means adapted to hold said side frames in spaced 20 relation, the front vertical rails and upper longitudinal rails being cut away to leave a space, and an angular skeleton frame fitting said space and hinged to the upper ends of the front vertical rails aforesaid.

10. In a skeleton supporting frame for the wall panels of the enclosing casing of a portable motion picture machine, a pair of skeleton side frames formed with central rings adapted to support the pair of film reel 25 magazines of the machine, with vertical and longitudinal rails integrally connected to said rings, with transverse bracing means adapted to hold said side frames in spaced relation, the front vertical rails and upper 30 longitudinal rails being cut away to leave a space, and an angular skeleton frame fitting said space and hinged to the upper ends of the front vertical rails aforesaid, and provided with stop extensions at its lower end.

11. In a skeleton supporting frame for the wall panels of the enclosing casing of a portable motion picture machine, a pair of skeleton side frames formed with central rings adapted to support the pair of film reel 40 magazines of the machine, with vertical and longitudinal rails integrally connected to said rings, with transverse bracing means

adapted to hold said side frames in spaced relation, the front vertical rails and upper longitudinal rails being cut away to leave a space, and an angular skeleton frame fitting 50 said space and hinged to the upper ends of the front vertical rails aforesaid, and comprising a central orificed web and angular side rails integrally connected together. 55

12. In a skeleton supporting frame for the wall panels of the enclosing casing of a portable motion picture machine, a pair of skeleton side frames formed with central rings 60 adapted to support the pair of film reel magazines of the machine, with vertical and longitudinal rails integrally connected to said rings, with transverse bracing means adapted to hold said side frames in spaced relation, the front vertical rails and upper 65 longitudinal rails being cut away to leave a space, and an angular skeleton frame fitting said space and hinged to the upper ends of the front vertical rails aforesaid, and comprising a central orificed web and angular 70 side rails and a transverse corner rail integrally connected together.

13. In a skeleton supporting frame for the wall panels of the enclosing casing of a portable motion picture machine, a pair of skeleton side frames formed with central rings 75 adapted to support the pair of film reel magazines of the machine, with vertical and longitudinal rails integrally connected to said rings, with transverse bracing means 80 adapted to hold said side frames in spaced relation, the front vertical rails and upper longitudinal rails being cut away to leave a space and an angular skeleton frame fitting 85 said space and hinged to the upper ends of the front vertical rails aforesaid, and comprising a central orificed web and angular side rails and a transverse corner rail integrally connected together, the side rails having stop extensions at their lower ends. 90

Signed at Fond du Lac, Wis., this 30th day of October 1922.

CHAS. LEO FITZ.
